COMBINED MIXING AND STAINING
DENTAL TRAYFrederick L. Towe, 4826 Gentry Ave.,
North Hollywood, Calif. 91607

Filed Dec. 22, 1966, Ser. No. 5,146

Term of patent 14 years

(Cl. D24—1)

FIGURE 1 is an elevation of a combined mixing and staining dental tray showing my new design;

FIGURE 2 is an end elevation thereof;

FIGURE 3 is a top plan view of the cover and base;

FIGURE 4 is a top plan view of the base;

FIGURE 5 is a bottom view of the cover;

FIGURE 6 is a bottom view of the base;

FIGURE 7 is a cross-sectional view taken along a line 7—7 of FIGURE 2;

FIGURE 8 is a cross-sectional view taken along a line 8—8 of FIGURE 1; and

FIGURE 9 is an elevational view similar to FIGURE 1 but illustrating the cover removed from the base.

I claim:

The ornamental design for a combined mixing and staining dental tray, as shown and described.
